US00D666510S

(12) **United States Design Patent**
Beland et al.

(10) **Patent No.:** US D666,510 S
(45) **Date of Patent:** ** Sep. 4, 2012

(54) **THERMOSTAT HOUSING**

(75) Inventors: **Stephane Joseph Pierre Beland**, St-Jean-sur-Richelieu (CN); **Tomas Peciva**, Slusovice (CZ); **Tarik Khoury**, Brno-Jundrov (CZ); **Heidi Finch**, Champlin, MN (US); **Pavel Kalina**, Brno-Medlanky (CZ)

(73) Assignee: **Honeywell International Inc.**, Morristown, NJ (US)

(**) Term: **14 Years**

(21) Appl. No.: **29/399,697**

(22) Filed: **Aug. 17, 2011**

(51) **LOC (9) Cl.** 10-04

(52) **U.S. Cl.** **D10/50**

(57) **CLAIM**

The ornamental design of the thermostat housing, as shown and described.

DESCRIPTION

FIG. 1 is a perspective view of a thermostat housing; FIG. 2 is a front elevation view of the thermostat housing of FIG. 1; FIG. 3 is a left elevation view of the thermostat housing of FIG. 1; FIG. 4 is a right elevation view of the thermostat housing of FIG. 1; FIG. 5 is a top view of the thermostat housing of FIG. 1; FIG. 6 is a bottom view of the thermostat housing of FIG. 1; FIG. 7 is a perspective view of another thermostat housing; FIG. 8 is a front elevation view of the thermostat housing of FIG. 7; FIG. 9 is a left elevation view of the thermostat housing of FIG. 7; FIG. 10 is a right elevation view of the thermostat housing of FIG. 7; FIG. 11 is a top view of the thermostat housing of FIG. 7; and, FIG. 12 is a bottom view of the thermostat housing of FIG. 7. The portions illustrated in broken lines on the figures are for illustrative purposes only and form no part of the claimed design.
